UNITED STATES PATENT OFFICE

112,579

DESIGN FOR A STORE FRONT

David G. Ross, Los Angeles, Calif., assignor to Welch's Candy, Limited, Los Angeles, Calif., a corporation of California

Application May 16, 1938, Serial No. 77,216

Term of patent 14 years

To all whom it may concern:

Be it known that I, David G. Ross, a citizen of the United States, residing at Los Angeles, in the county of Los Angeles, State of California, have invented a new, original, and ornamental Design for Store Fronts, of which the following is a specification, reference being had to the accompanying drawing, forming part thereof.

The drawing shows in Fig. 1, a front elevational view of a store front; and Fig. 2 shows a sectional elevation of the same embodying my new design.

I claim:

The ornamental design for a store front, as shown.

DAVID G. ROSS.
